Primary Examiner — Richard Edgar*Assistant Examiner* — Jessica Ruth Grable(74) *Attorney, Agent, or Firm* — Daniel M. Cohn;
 Howard M. Cohn(57) **CLAIM**

The ornamental design for a rotating shelf, as shown and described.

DESCRIPTION

FIG. 1 is a perspective view of a rotating shelf showing my new design;

FIG. 2 is another perspective view thereof;

FIG. 3 is an exploded perspective view of the rotating shelf;

FIG. 4 is a front elevational view thereof;

FIG. 5 is a rear elevational view thereof;

FIG. 6 is a left side elevational view thereof;

FIG. 7 is a right side elevational view thereof;

FIG. 8 is a top plan view thereof; and,

FIG. 9 is a bottom plan view thereof.

The circle shown with a broken line in FIGS. 2 and 9 is a portion of the rotating shelf and forms no part of the claimed design. The broken lines showing the jar is for the purpose of illustrating environmental structure and form no part of the claimed design.

1 Claim, 9 Drawing Sheets(56)
